SWIMMING POOL COPING BLOCK

Leslie N. Jefferson, 5042 Kohn Way, Carmichael, Calif.,
and Lawrence J. Jerue, Jr., 7045 Lincoln Oaks Drive, Fair Oaks, Calif.

Filed June 1, 1965, Ser. No. 85,540

Term of patent 14 years

(Cl. D13—1)

FIG. 1

FIG. 2

FIGURE 2 is an elevational view of one end thereof to an enlarged scale, the other end being substantially similar in appearance;

We claim:

The ornamental design for a swimming pool coping block, as shown and described.
